UNITED STATES PATENT OFFICE.

ROBERT J. VAUGHAN, OF HAMILTON, OHIO.

DESIGN FOR A COMBINED COLLAPSIBLE CONTAINER AND CLOSURE THEREFOR.

Application filed April 24, 1926. Serial No. 17,438. Term of patent 14 years.

To all whom it may concern:

Be it known that I, ROBERT J. VAUGHAN, a citizen of the United States, residing at Hamilton, in the county of Butler and State of Ohio, have invented a new, original, and ornamental Design for Combined Collapsible Container and Closure Therefor (Case A), of which the following is a specification, reference being had to the accompanying drawing, forming part thereof.

Fig. 1 is a front elevation of my new design for combined collapsible container and closure therefor.

Fig. 2 is a side view thereof.

I claim:

The ornamental design for a combined collapsible container and closure therefor as shown.

ROBERT J. VAUGHAN.
